UNITED STATES PATENT OFFICE.

THOMAS W. HOBBDAY, OF EAST BOSTON, MASSACHUSETTS.

DRESS-FORM.

SPECIFICATION forming part of Letters Patent No. 427,991, dated May 13, 1890.

Application filed December 26, 1888. Serial No. 294,590. (No model.)

To all whom it may concern:

Be it known that I, THOMAS W. HOBBDAY, a citizen of the United States, residing at East Boston, in the county of Suffolk and State 5 of Massachusetts, have invented certain new and useful Improvements in Dress-Forms; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 Figure 1 is a representation chiefly in vertical section of a dress-form made in accordance with my invention; Fig. 2, a horizontal section on line 2 2 of Fig. 1, showing in top view the mechanism for varying the size of 20 the neck portion of the waist-sections. Fig. 3 is a horizontal section on line 3 3 of Fig. 1. Fig. 4 is an inner side view of two next adjacent edge bands and links of two adjoining sections of the skirt-frame of the form. Fig. 25 5 is an edge view of one of the said edge bands and its link. Fig. 6 is an inner side view of the lower portion of one of the waist-sections and of the upper portion of one of the skirt-sections, showing the way of connecting each to the other. Fig. 7 is a horizontal section on line 7 7 of Fig. 1, showing in top view the mechanism for changing the size of 30 the form in its waist and skirt portions. Fig. 8 is a back view, and Fig. 9 a vertical section, of a portion of the back section of the skirt-frame provided with a bustle. Fig. 35 10 is a perspective view of one of the eyes r' in which the braces q' of the bustle swivel. Fig. 11 is a horizontal section on line 13 13 of 40 Fig. 1.

The nature of my invention is defined in the claims hereinafter presented.

In the drawings, a denotes the top portion of the stand in which the tube or upright b , 45 which has connected to it the parts for supporting and operating the sections of the form, is sustained and pivoted, the said tube b having a collar a^2 secured to it by a set-screw. Said collar resting on the top of the 50 stand a admits of the form being raised or

lowered, as may be desired, and also revolved in the stand.

In Fig. 1 to the lower part of the tube b is fixed a supporter A , having radial arms on which are arranged slides c , provided with ears or 55 guides d , which extend or bear against the edges of the said arms and guide the slides when moved thereon. The outer ends of the slides c turn upward at e , enter sockets f in the form, and sustain the sections thereof in 60 position.

Arranged within the tube b is a rod h , the lower end of which extends a little below the supporter A , and its upper end projects above the top of said tube b and has fixed to it a 65 knob K , said knob being chambered to receive the upper portion of said tube and turn loosely about it, and has a clamp-screw j for fixing it to said tube. The said knob K is provided with a scale k , as shown. Supported 70 on the sleeve i' of the supporter A , and so as to turn thereon, is an adjuster C , it being connected to the rod h by a pin f' , which is introduced through a slot h' in the sleeve i' , and another slot g' in the tube b and into a socket 75 e' in the said rod, and is then dropped into a notch k' in said adjuster. (See Figs. 1 and 11.) The adjuster C is held in place on the sleeve of the supporter A , and the pin f' is kept in place therein by a flanged collar l' , secured to the said sleeve i' and to the tube b by a set-screw m^2 . The said adjuster C is provided with curved grooves m , arranged eccentrically to the axis of the said tube b . (See Fig. 7.)

85 Projecting from the slides c are pins n , which enter the grooves m in the adjuster, as shown. By loosening the set-screw j and turning the knob K the adjuster C will turn on its axis and move the slides c , and consequently the sections of the form, the index p , hereinafter referred to, denoting on the scale k when the form is adjusted in its waist portions to the size desired. Below the knob K is another knob L , provided with a scale o , as 90 shown, and also with a set-screw q for fixing the knob L and adjuster D to the tube b when the neck of the form is adjusted to the required size. The said knob L is driven tightly on a sleeve forming a part of said adjuster D , 95 100

and the index p , arranged between the knobs and fixed to the tube b , operates with the scale o to denote the size of the form in its neck portion.

5 The adjuster D is shown in Fig. 2 as formed with curved arms m' arranged eccentric to its axis, said arms passing through staples n' fixed to the slides c' , and the said slides are represented in Fig. 1 as pivoted at their outer 10 ends to the form-sections. This construction is essentially the same in principle, and is practically the same in operation as the mechanism shown in Figs. 1 and 7 for adjusting the waist portions of the form.

15 Below the adjuster D is arranged a supporter B, of like construction to the supporter A, it being clamped to the tube b by a set-screw r , which passes through the hub of the said adjuster and bears against the said tube. 20 Said supporter B sustains the slides c' of the neck-adjusting mechanism.

The waist-sections of the form at their lower ends are provided with sockets t and turn-buttons u , as shown, the sockets receiving the 25 top ends of the wires v of the skirt-sections, and the turn-buttons, after passing into the slots w of the edge bands or strips x of the said skirt-sections, are turned into the position shown in Figs. 6 and 7, so as to lock the said skirt-sections to the waist-sections. The said edge strips x are also provided with links z , each pivoted at one end to one of the strips, the free end of one link having a slot a' to receive a turn-button d' , pivoted to the free 30 end of the next adjacent link. This way of connecting the ends of the links admits of the ready separation of the skirt-sections from each other when desired.

To the upper horizontal wire o' of the rear 40 skirt-section is pivoted a flat spring p' , to which are pivoted two braces q' , provided at their ends with eyes r' , in which said braces swivel. Said eyes encircle the wires v of said skirt-section and are adapted to slide thereon, 45 so as to admit of the spring p' being curved and sustained by the braces in the position shown in full lines in Fig. 9, to serve as a bustle R, and when not required for use the eyes can be slid downwardly on the wires, so 50 that the braces and the spring will take the position shown in dotted lines in said Fig. 9.

From the foregoing it will be seen that by 55 unscrewing the set-screw j and turning the knob K the adjuster C will be moved on its axis by the pin f' connected to it and to the rod h , said pin moving in the slots g' and h' , (see Fig. 11,) and admitting of the necessary 60 movement of said adjuster to carry the slides c from one extreme to the other of their range of motion, the different sizes to which the 65 waist-band of the form can be adjusted being indicated on the scale k by the index p . The screw j serves to clamp the waist-adjusting mechanism in position when adjusted to the required size. By loosening the set-screw q the knob L can be turned on the upright b

and the adjuster D caused to vary the size of the neck of the form, the size being indicated on the scale o by the index p .

Having described my invention, what I claim is—

1. The combination of the knob L, provided with a scale o and set-screw q , the adjuster D, fixed to said knob, the tube b , sustained in the stand, the index p , the supporter B, having radial arms and fixed to the tube, the slides sustained and guided on said arms, connected to the adjuster and to the neck of the form, with the said neck portions of the form, substantially as shown and set forth. 80

2. The combination of the tube b , slotted at g' and supported in the stand, the supporters A B, fixed thereto, the slides adapted to move in a radial direction on the arms of said supporters and connected to the form-sections and to the adjusters, the rod h , having the socket e' , the knob K, fast to the said rod and provided with a set-screw, the adjuster C, connected to said rod, the pin f' , the adjuster D, the knob L, fixed thereto and 90 having set-screw, with the sections of the dress-form, all being arranged and supported substantially as shown and set forth.

3. The combination of the tube b , the slot g' therein, the stand sustaining said tube, the supporters A and B, fixed to said tube, the slides adapted to move in radial directions on the arms of said supporters and connected to the form-sections and to the adjusters, the rod h , the socket e' therein, the knob K, fast 100 to said rod, set-screw j , the adjuster C, the notch k' therein, the pin f' , the adjuster D, the knob L, fixed thereto, set-screw q , the slot h' in sleeve of supporter A, the flanged collar l' , and set-screw m^2 , with the sections of 105 the dress-form, all substantially as shown and set forth.

4. The waist-sections of the form provided with the sockets t and turn-buttons u , in combination with the wires v and notched-edge 110 strips x of the skirt-sections, substantially as shown, and for the purpose set forth.

5. In a dress-form, the combination of the skirt-sections thereof with the links z z , one link pivoted to one section and slotted as 115 shown, the other link pivoted to the next adjacent section and provided with a turn-button connected to it and adapted to pass through the slot in the other link and connect the two, as set forth. 120

6. In a dress-form, the combination of the wires v v and o' thereof with the bustle-strip p' , pivoted to said wire o' , as shown, the braces q' , pivoted to the bustle-strip and to eyes r' , with said eyes arranged to slide on the said 125 wires v v to admit of the bustle-strip being elevated into position for use or depressed within the form, essentially as shown and set forth.

7. The combination of the tube b , provided 130 with the slot g' and supported in the stand, the supporter A, fixed to said tube and pro-

vided with radial arms, the slides *c*, arranged to move on said arms, connected to the waistband of the form and to the adjuster *C*, the said adjuster having grooves eccentric to its 5 axis and a notch *k'*, the rod *h* having the notch *e'* and arranged within the tube *b*, the knob *K*, fixed to said rod, the pin *f'*, connecting said rod and adjuster with the skirt-form sections, supported by the slides and

connected to each other by the links *z*, said 10 links detachably connected, essentially as shown, and for the purpose set forth.

In testimony whereof I affix my signature in presence of two witnesses.
